United States Patent

Des. 238,498

Patented Jan. 20, 1976

238,498

PET HOUSE

Katie H. Barr, 7121 Bull Run Post Office Road,
Centerville, Va. 22020

Filed Apr. 22, 1974, Ser. No. 462,726

Term of patent 14 years

Int. Cl. D30—02

U.S. Cl. D30—1

FIG. 1

FIG. 2

FIG. 3

FIG. 4

FIG. 1 is a perspective view of a pet house showing my new design;

FIG. 2 is a front elevational view of the pet house shown in FIG. 1;

FIG. 3 is a side elevational view of the pet house shown in FIG. 1 as viewed from the right; and

FIG. 4 is a top plan view of the pet house shown in FIG. 1.

The undisclosed left side and rear elevational views are substantially the same as the right side disclosed in FIGS. 1 and 3, but without the pocket.

I claim:

The ornamental design for a pet house, as shown and described.
